FRANK H. SCHWERIN, OF WEST VIEW, PENNSYLVANIA, ASSIGNOR TO THE DUFF MANUFACTURING COMPANY, OF PITTSBURGH, PENNSYLVANIA, A CORPORATION OF PENNSYLVANIA.

OIL-WELL JACK.

Application filed August 2, 1923. Serial No. 655,155.

The invention relates to oil well jacks for wrenching and unwrenching the sections of the drills. In some cases the screw parts when they have remained jammed together become frozen, so that it is very difficult to disconnect them when desired by the ordinary ratcheting operation. The present invention aims to provide a strong, reliable, easily operated and powerful construction in connection with the back-post, for starting the unwrenching operation, which may then be continued by means of the traveling jacking post.

In the accompanying drawing forming part hereof:

Fig. 1 is a perspective view illustrating the use of the jack;

Fig. 2 is a side elevation of the improved back-post on the rail, portions being broken away and in section; and

Fig. 3 is a cross-section on the line 3—3 of Fig. 2.

An oil-well jack has a rail 1, usually bent into the segment of a circle, and having ratchet teeth 2 cut in the top of its head over the major portion of its length. Slidable on the rack part of the rail is a jacking-post 3 containing single- or double-acting pawl mechanism operable by a lever bar inserted in a lever socket 4 to cause the post to advance along the rail in a familiar manner.

In use one of a pair of wrenches 5 rests against the beak of this traveling post, while the other wrench rests against a back-post. The two wrenches grip adjacent drill sections 6, and in one arrangement of the wrenches ratcheting of the traveling post will cause the sections to be screwed together, while by reversing the positions of the wrenches the same operation will cause unscrewing. Sometimes, however, excessive resistance is encountered in the very beginning when effort is made to separate the sections in this manner.

In order to provide means for breaking the "freeze" and at the same time to insure as strong and reliable a jack as formerly, the present improved back-post construction has been devised.

At the rear portion 7 of the rail, which is preferably free of rack teeth, there is securely applied and bolted a fixed post 8, having a horizontal opening through it

above and tangential with respect to the curve of the rail. Another post 9 of massive construction, having a beak at the front to coact with one of the wrenches, is also engaged with the rail, but in such manner as to be slidable. For this purpose it is formed with lateral basal slotted and flanged portions 10, which embrace and engage under the head of the rail and are of such length and conformation as to afford steady bearing.

The slidable back-post thus supported and guided, is sustained and adapted to be operated by a screw 11 having a shaft portion 12 which is journaled in the opening through the fixed back-post 8. A collar 13 on the screw bearing against the fixed post holds the screw against thrust, and at the opposite side of the post a ratchet wheel 14 is fixed to the projection of the shaft for operation by the pawl of a ratchet-lever 75 socket 16, which is pivoted on the shaft.

The screw portion of the shaft passes through a nut 15 into a cavity 17 in the slidable back-post 9, the nut being received in the outer part of this recess where it is sustained against thrust by a shoulder 18 on the nut. The cavity is made larger than the screw and nut, and the shoulder 18 and the cooperating face 19 on the post block are made on a spherical curvature, giving the effect 85 of a ball and socket. This prevents binding of the straight screw as it forces the slidable block to move on the curved rack, and also allows for any inaccuracy in relation between the parts. Ribs on the block entering slots in the nut, as indicated at 20, prevent the nut from turning, while permitting the desired flexibility.

While the preferred form of the invention has been described in detail, it should be understood that I do not necessarily limit myself to the precise construction.

What I claim as new is:

1. In an oil-well jack having a rack rail and a traveling jacking post adapted to be ratcheted along the rail, a back-post fixed on the rail near one end, a slidable back-post having bearing engagement with the rail in front of the fixed back-post, and a screw operable by a lever to act between the fixed and slidable posts.

2. In an oil-well jack having a rack rail and a traveling jacking post adapted to be

ratcheted along the rail, a back-post fixed on the rail near one end, a slidable back-post having bearing engagement with the rail in front of the fixed back-post, a screw operable by a lever to act between the fixed and slidable posts, a ratchet wheel fixed on the screw, and a pivoted ratchet lever.

3. A back-post for an oil-well jack, comprising a back-post adapted to be fixed to the rack rail, a massive slidable back-post having a beak to coact with a wrench and lateral basal guide portions adapted to engage the head of the rail so as to be guided and braced thereby, said slidable back-post containing a nut, a screw journaled in the fixed back-post and in threaded engagement with the nut, and ratchet lever mechanism for operating the screw.

4. In an oil-well jack having a rack rail and a traveling jacking post adapted to be ratcheted along the rail, a fixed back-post on the rail, a movable back-post having sliding bearing on the rail in front of the fixed back-post, a screw held rotatably in the fixed back-post, a ratchet lever to operate the screw, and a nut for the screw flexibly seated in the slidable back-post.

5. In an oil-well jack having a rack rail and a traveling jacking post adapted to be ratcheted along the rail, a fixed back-post

on the rail, a movable back-post having sliding bearing on the rail in front of the fixed back-post, a screw held rotatably in the fixed back-post, a ratchet lever to operate the screw, said slidable back-post containing a cavity having a curved seat at its entrance; a nut having a curved flange bearing on the seat, and means to keep the nut from turning.

6. In an oil-well jack having an arcuate rack rail, a back-post fixed on the rail, a slidable back-post constructed for bearing engagement with the rail in front of the fixed back-post, a screw having thrust bearing against one of said back-posts, and a nut for said screw rockingly seated in the other back-post.

7. In an oil-well jack having an arcuate rack rail, a back-post fixed on the rail, a slidable back-post constructed for bearing engagement with the rail in front of the fixed back-post, a nut in the slidable back-post, a screw engaging said nut and having thrust bearing against the fixed back-post and a journal portion passing through said post, a ratchet-wheel on the projection of said screw at the back of said fixed back-post, and a ratchet-lever pivoting about said projection.

FRANK H. SCHWERIN.
